US0D1061976S

(12) **United States Design Patent** (10) **Patent No.:** **US D1,061,976 S**
(45) **Date of Patent:** **** Feb. 11, 2025**

(54) **LAMP**

- (71) Applicant: **POWER BEAUTY(DONGGUAN) INDUSTRIAL CO., LTD.**, Dongguan (CN)
- (72) Inventor: **Yiqun Xu**, Dongguan (CN)
- (73) Assignee: **POWER BEAUTY(DONGGUAN) INDUSTRIAL CO., LTD.**, Dongguan (CN)

(**) Term: **15 Years**

(21) Appl. No.: **29/880,770**

(22) Filed: **Jul. 27, 2023**

(51) **LOC (15) Cl.** **26-02**

(52) **U.S. Cl.**

USPC **D26/40**; D26/106

(58) **Field of Classification Search**

USPC D26/60, 24, 47, 49, 50, 51, 61–65, 78, D26/93–113, 118, 138, 10, 54, 154, 40; D21/500, 506–511; D14/203.2, 207; D30/110–112, 124–126

CPC F21V 35/00; F21V 35/006; F23D 3/02; F23D 3/16; C11C 5/00

(57) **CLAIM**

The ornamental design for a lamp as shown and described.

DESCRIPTION

FIG. 1 is a perspective view of a lamp showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the lamp that form no part of the claimed design.

1 Claim, 8 Drawing Sheets
